BED PATIENT ELEVATOR

Orice J. Brouillette, Galesburg, Ill.

Application March 7, 1950, Serial No. 148,141

2 Claims. (Cl. 5—86)

1 This invention relates to surgical appliances particularly as used for invalids or patient in hospitals, and in particular the invention relates to a patient carrying platform or stretcher, supported from a base with telescoping posts and in which hydraulic means is provided for extending the height of the posts to elevate the platform with a patient thereon.

The purpose of this invention is to provide a patient carrying hoist in which a patient may be raised by a small foot pedal actuated hydraulic pump and in which the platform may be tilted about the center to raise and lower either end.

Various devices have been provided for handling invalids and patients, and for removing patients from hospital beds but it is difficult for a nurse to move the patient from the bed to the platform of the hoist or carriage. With this thought in mind this invention contemplates a platform formed with spaced straps extended across side bars of a rectangular shaped frame, pivotally supported at the center from base elements with telescoping posts and in which elevating means is provided in combination with the base elements for extending the posts to elevate the platform.

The object of this invention is, therefore, to provide means for forming an elevator for bed patients in which a patient carrying platform thereof may be extended under a patient on a bed and in which the platform is pivotally mounted whereby it may be elevated with either end high.

Another object of the invention is to provide a bed patient elevator upon which a patient may be placed by a nurse without discomfort to the patient.

Another object of the invention is to provide a bed patient elevator that is elevated by a foot pedal actuated hydraulic pump.

A further object of the invention is to provide a bed patient elevator having a patient carrying platform that is assembled under a patient on a bed and in which the platform is elevated by a foot pedal actuated hydraulic pump with the platform in a horizontal or sloping position, which is of a comparatively simple and economical construction.

Other features and advantages of the invention will appear from the following description taken in connection with the drawings wherein:

Figure 1 is a side elevational view showing the bed patient elevator with the hydraulic pump and control valve associated therewith extended toward one end of the elevator.

2 Figure 2 is a plan view of the platform of the elevator with part broken away showing the hydraulic pump and the housing therefor with the housing shown in section.

5 Figure 3 is a cross section through the elevator taken on line 3—3 of Figure 1.

Figure 4 is a vertical section through one of the telescoping posts at one side of the elevator with parts broken away and parts shown in 10 elevation.

Figure 5 is an elevational view showing the gear casing at the upper end of one of the posts and showing the hand actuated knob for tilting the platform.

15 Figure 6 is a vertical section through the gear casing taken on line 6—6 of Figure 4.

Figure 7 is a detail showing the groove or keyway between the telescoping elements of the posts.

20 Figure 8 is a detail showing a portion of the outer telescoping tube of one of the posts and showing a key socket in the wall thereof.

Figure 9 is a cross section through the telescoping posts taken on line 9—9 of Figure 7 and 25 showing the outer and inner tubes thereof.

Figure 10 is a detail illustrating the piston used in the telescoping posts with the piston ring omitted.

Figure 11 is a plan view of the piston shown 30 in Figure 10.

Figure 12 is a detail showing a sectional plan through one of the corners of the patient carrying platform illustrating the mounting of the cross bars at the ends of the side bars of the 35 platform.

Figure 13 is a sectional view through one of the corners of the frame.

Figure 14 is an exploded view illustrating the 40 end or cross bar separated from the end of the side bar and showing the inner side of the end of the side bar.

Figure 15 is a detail illustrating the arrangement of the valves for connecting the discharge of the pumps to the telescoping posts with the valves shown in the position of elevating the platform.

Figure 16 is a similar view showing the valves in the position of lowering the platform.

Figure 17 is a view illustrating a modification wherein the platform is supported on truck elements extended at one end to facilitate positioning the platform over a bed and the like.

55 Figure 18 is a sectional plan taken on line 18—18 of Figure 17.

Figure 19 is a sectional view taken on the line 19—19 of Figure 1.

Referring now to the drawings wherein like reference characters denote corresponding parts in the bed patient elevator of this invention includes a platform formed with spaced straps 10 extended across side bars 11 and 12, telescoping posts formed with outer tubes 13 and 14 and inner tubes 15 and 16, respectively and the posts are supported on a base having side arms 17 and 18 connected by a cross tube 19.

The side bars 11 and 12 are pivotally mounted in the center of the platform in gear casings 20 and 21 by stub shafts 22 and 23, respectively. The shafts extend through sleeves 24 and 25 in which the side bars 11 and 12 are mounted and the sleeves are positioned between upwardly extended ends 26 and 27 of the casing 20 and 28 and 29 of the casing 21. The stub shafts 22 and 23 extend through the upwardly extended ends 26 and 27 of the gear casing 20 and 28 and 29 of the casing 21. The stub shafts 22 and 23 extend through the upwardly extended ends 26 and 27 of the gear casing 20 and 28 and 29 of the casing 21. The stub shafts 22 and 23 extend through the upwardly extended ends 26 and 27 of the gear casing 20 and 28 and 29 of the casing 21. The stub shafts 22 and 23 extend through the upwardly extended ends 26 and 27 of the gear casing 20 and 28 and 29 of the casing 21. The stub shafts 22 and 23 extend through the upwardly extended ends 26 and 27 of the gear casing 20 and 28 and 29 of the casing 21. The stub shafts 22 and 23 extend through the upwardly extended ends 26 and 27 of the gear casing 20 and 28 and 29 of the casing 21. The stub shafts 22 and 23 extend through the upwardly extended ends 26 and 27 of the gear casing 20 and 28 and 29 of the casing 21.

The gear casings 20 and 21 are similar and the same reference numerals are used on the interior parts of each. As illustrated in Figure 4 the stub shaft 23 is provided with a gear segment 30 that meshes with a worm gear 31 on a shaft 32 and the shaft 32 is provided with the worm gear 33 that meshes with a worm 34 on a shaft 35, on the outer end of which a hand wheel 36 is provided and with the hands wheels extended from the gear casings on each side of the platform the platform may readily be tilted or held in a horizontal position depending upon the patient.

The ends of the side bar 11 are provided with caps 37 and 38, as shown in detail in Figures 12, 13, and 14 and the ends of the side bar 12 are provided with similar caps 39 and 40. The caps are provided with plugs 41, as shown in Figure 12 and end tubes 42 and 43 are mounted on the plugs.

The ends of the straps 10 at one side of the platform are wrapped around the side bar 11 and secured to the bar by stitches 44 and the ends of the straps at the opposite side of the platform are provided with buckles 45 that receive short straps 46 positioned on the cross bar 12, as shown in Figures 1 and 2. With the straps arranged in this manner the ends of the straps 10 are released from the straps 46 so that the straps 10 may be extended under a patient on the bed and then secured to the straps 46 by the buckles 45 whereby the patient carrying platform is assembled under the patient without disturbing the patient and without overexertion on the part of the nurse.

The telescoping posts 13 and 14 are formed as illustrated in Figure 4 with the upper outer sections 13 and 14 slidable over the lower sections 15 and 16. The pistons and packing glands in both posts are similar and the same reference numerals are used for both. As illustrated in Figure 4 the tube 14 is provided with a bushing 47 in which a piston rod 48 of a piston 49 is carried and the piston is slidably mounted in the inner or lower tube 16, which forms the cylinder. To place the patient-carrying platform in position on the bed, the telescopic posts 13 and 14 are raised and then the platform of the present invention is moved longitudinally along the bed. The end of the bed can be manually lifted in order to clear the crossbar 19.

The piston 49 which is secured on the lower end of the rod 48 is provided with an annular groove

75 inders, valves and posts.

50 for a piston ring 51 and, as illustrated in Figure 4 the upper end of the tube 16 is provided with a packing gland 52 and the upper end of the packing gland is provided with an opening 53 for a spanner wrench or the like. The outer surface of the tube 16 is provided with a keyway 54 and a key 55, positioned in a socket 56 in the outer tube 14 travels in the groove 54.

The lower ends of the inner tubes of cylinders 15 and 16 are positioned in T's 57 and 58 in which the end sections of the base arms 17 and 18 are secured and, as illustrated in Figure 1 extend upwardly and over in the form of goose necks and casters 59 are provided on the outer ends. The cross tube 19 connects the fittings 57 and 58, as shown in Figure 3 providing communicating means between the lower ends of the cylinders of the posts.

The platform is elevated by hydraulic cylinders 60 and 61 mounted on a platform 62 and actuated by a foot lever 63 which is pivotally mounted on the platform by hinges 64 and connected to piston rods 65 and 66 of the cylinders by links 67 and 68, respectively, as illustrated in Figures 1 and 2. A spring 69 is provided between the lower end 70 of the foot lever and a clip 71 for returning the lever to the upper position, as shown in Figure 1.

The discharge connections of the cylinders 60 and 61 are connected, as illustrated in Figures 15 and 16 to valves 72 and 73 and valve 72 is actuated by a foot lever 74 through a cam 75, whereby with the valve 72 closed, as shown in Figure 15, fluid under pressure from the cylinders 60 and 61 35 passing through the valve 73 from the tube 16 is admitted to the cylinders 15 and 16 through the tube 77 and connections 78 and 79. When it is desired to release the fluid pressure in the cylinders 15 and 16 to lower the platform the foot lever 74 is pressed downwardly whereby the cam 75 opens the valve 72 so that fluid from the connections 78 and 79 is permitted to escape through a connection 80. The hydraulic fluid passing through the exhaust conduit 80 enters a reservoir or tank 98, while the hydraulic fluid passing from the tank 98 passes through a line 96 to the conduit 76, there being a check valve 97 arranged in the line 96.

With the parts arranged in this manner the elevating device may be positioned over a bed with the straps extended under a patient and by working the foot lever 63 the posts at the sides are extended to elevate the platform, and by actuating the foot lever 74 the pressure is relieved whereby the platform will be lowered.

The platform may be used in a horizontal position or either end may be elevated by turning the hand wheel or knob 36.

In the design illustrated in Figures 17 and 18 a platform 81 supported by telescoping posts 82 and 83, is mounted on a truck having side rails 84 and 85, with T's 86 and 87, similar to the T's 57 and 58, connecting the lower ends of the posts to the rails, and in this design the rail 84 is provided with arcuate ends 88 and 89 and the rail 85 with arcuate ends 90 and 91. The ends of the rails are provided with casters 92 and the extended ends 88 and 90 are provided with transversely disposed rods 93 and 94 on which a pump platform 95 similar to the platform 62 is positioned. In this design the elevator is provided with pump cylinders similar to the cylinders 60 and 61 and valves similar to the valves 72 and 73, with suitable connections between the pump cylinders, valves and posts.

With the parts arranged in this manner the elevator may readily be rolled over a bed from one end thereof and also readily rolled from the bed.

It will be understood that other modifications may be made in the design and arrangement of the parts without departing from the spirit of the invention.

What is claimed is:

1. In an elevator for bed patients, the combination which comprises a rectangular shaped frame having spaced side and end members with spaced straps having buckles therein extended across the said side members, a plurality of telescoping posts extended downwardly from the said side member of the frame and positioned midway of the length of the said side members, gear casings mounted on the upper ends of the posts and in which the side members of the rectangular shaped frame are pivotally mounted, means in said gear casing for elevating either end of the rectangular shaped frame, base members carried on casters on which the said posts are mounted, means connecting the lower ends of the posts, foot pedal actuated hydraulic cylinders carried by the said base members and having connections to the lower ends of the telescoping posts for extending the height of the posts, valves in the said connections, and means for supplying fluid under pressure to the lower ends of the posts for extending the length of the posts.

2. In an elevator for bed patients, the combination which comprises a rectangular shaped frame having spaced side and end members with spaced straps having buckles therein extended across the said side members, a plurality of tele-

scoping posts extended downwardly from the said side members of the frame and positioned midway of the length of the said side members, gear casings mounted on the upper ends of the posts and in which the side members of the rectangular shaped frame are pivotally mounted, means in said gear casing for elevating either end of the rectangular shaped frame, base members carried on casters on which the said posts are mounted, means connecting the lower ends of the posts, foot pedal actuated hydraulic cylinders carried by the said base members and having connections to the lower ends of the telescoping posts for extending the height of the posts, valves in the said connections, and means for actuating the valves in the said connections for holding the fluid in the posts and also for releasing the fluid from the posts to lower the platform.

ORICE J. BROUILLETTE.
